UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

STOKER FURNACE.

Application filed December 14, 1921. Serial No. 522,361.

To all whom it may concern:

Be it known that I, HERMAN A. POPPENHUSEN, a citizen of the United States, residing at Hammond, in the county of Lake and State of Indiana, have invented new and useful Improvements in Stoker Furnaces, of which the following is a specification.

This invention relates to furnaces, and more particularly to furnaces equipped with mechanical stokers, such as chain grates, and provided with vertical air ducts at the sides of the grate for supplying the active grate surface from below with a forced draft delivered to the grate between the top and bottom leads thereof.

One object of my invention is to provide for the vertical air ducts at the sides of the grate, a main air supply conduit, common to all of said vertical ducts, for avoiding the expense of building and use of a plurality of separate supply conduits for the several vertical ducts as heretofore, and further for delivering a substantially steady and continuous flow of air to the grate by being able to maintain for all of the vertical ducts, regardless of their number, a substantially constant pressure in the main supply conduit.

Another object of my invention is to make the vertical ducts the full width of the compartments between the grate leads and into which these ducts open for giving a full and adequate supply of draft to the entire grate surface covering the compartments, and thus gain an efficient and economical combustion of the fuel being carried on the grate.

A further object of my invention is to arrange the main supply conduit between the vertical ducts at the opposite sides of the grate and have all of said ducts open into said conduit so that the latter may be located in the furnace setting between the side walls thereof and beneath the grate, thus retaining all of the draft supplying structure within the confines of the furnace and not projecting beyond the sides thereof to interfere with or hinder the building of furnaces side by side with their side walls in contact.

A still further object of my invention is to locate the main supply conduit directly beneath the lower lead of the grate and to partition said conduit from said lead by plates directly beneath said lead, thus en-

abling the height of the stoker from the bottom of said conduit to be reduced to the minimum.

Another object is to deliver the draft from the vertical conduits directly into the space between the grate leads and to seal the compartments into which said space is divided transversely by members bearing against the respective grate leads.

The invention consists further in the matters hereinafter described and more particularly set forth in the following claims.

In the accompanying drawings—

Fig. 1 is a longitudinal vertical sectional view of a chain grate stoker furnace embodying the features of my invention;

Fig. 2 is a transverse vertical sectional view taken on line 2—2 of Fig. 1;

Fig. 3 is an enlarged vertical sectional view taken through one side of the furnace, the damper being shown open;

Figs. 4 and 5 are perspective views of details of construction to be hereinafter described; and

Fig. 6 is a horizontal sectional view taken on line 6—6 of Fig. 1.

In the drawings, I have shown a furnace of the type embodying a mechanical stoker, such as a chain grate 1 located in the combustion chamber of the furnace and having upper and lower leads 2 and 3. Said grate 1 extends into said combustion chamber through the front wall of the furnace and has its rear or tail end terminating short of the bridge wall 4 to provide a vertical passage through which ash is discharged from the tail end of the grate into a hopper (not shown) below the grate as in furnaces of this general type. At the front of the furnace is a fuel hopper 5 through which fresh or green fuel is fed into the combustion chamber and onto the upper lead 2, which carries the fuel in a layer through the combustion chamber for consumption, as obvious.

The grate 1 extends horizontally between the side walls 6, 6 of the furnace setting, as shown in Fig. 2, and these walls each include a plurality of upright metal stools 7, 7 at the opposite sides of the grate. The stools 7, 7, in each wall, are laterally spaced apart the same distance and, in the particular furnace illustrated, there are four of such stools 7 in each side wall, with the stools in one wall aligned with those in the

opposite wall, as shown in Fig. 6. Said stools 7 rest on the bottom wall or floor 8 of the furnace setting, and extending between and secured to the stools in each wall 5 6 are metal frames 9, 9. Said frames 9 are spaced above the floor 8 and are vertically arranged with the openings therein normally closed by hinged doors 10 on the outside of said frames, as shown in Figs. 2, 8, 10 and 6.

Extending horizontally between and secured to the stools 7, 7 in line with the upper edges of the frames 9, 9 are channel bars 11. Said bars 11 extend along the side edges 15 of the upper grate lead 2 and have inwardly extending flanges on which the sides of the grate lead 2 rest. These bars 11 have adjustably mounted on them, ledge plates 12. The door frames 9 are spaced outward from 20 the side edges of the grate, and extending between them and the bars 11 are plates 13, 18. These also extend between the stools 7, 7, between which they are located, and close the spaces between the door frames 9 and bars 11, as shown in Figs. 2 and 3. The furnace floor 8 extends beneath the lower lead 3 and together with the structure to be hereinafter described forms an air supply conduit 14 extending the full width of the 30 stoker 1. In the furnace shown, the door frames 9 extend below the level of the lower lead 3 and metal plates 15 close the spaces between the lower margins of said frames 9 and the floor 8.

55 By the construction described, a plurality of vertical ducts 16, 16, 16 are provided on opposite sides of the grate 1 and all of these ducts communicate at their lower ends with the conduit 14, which is common to them 40 all and arranged between them, as shown in Fig. 6. The vertical ducts 16, 16 are closed at their upper ends by the plates 13, and open into the space between the grate leads 2 and 8 at opposite sides of the furnace.

45 This space is divided transversely into a plurality of compartments 17, 17, equal in number to the vertical ducts or passages 16, 16 at one side of the grate and communicating with them. To accomplish this I make 50 use of supporting skids or rails 18 for the upper grate lead 2. These skids 18 are laterally spaced apart and extend lengthwise of the grate 1 beneath the upper lead 2, as shown. Extending transversely across the 55 grate between the upper and lower leads 2, 3, are a plurality of vertically arranged channel members 19, 19. These are alinged with the several stools 7, 7 and are supported thereby, as shown in dotted lines in Fig. 60 3. Said members 19, 19 fit against the under sides of the skids 18, and between them and the under side of the top lead 2 are a plurality of members 20 shaped as shown in Fig. 1. Said members 20 extend between 65 and are supported by the skids 18 to close

the space between the members 19 and the under side of the top lead 2 and thus provide air seals between the several compartments 17, 17 along the upper lead 2. Moreover, said members 20 have wiping contact 70 with the under side of the top lead 2 so as not to hinder the movement thereof from the front to the rear of the furnace.

As shown in Fig. 1, the members 19 terminate short of the bottom lead 3, and for 75 closing the spaces between such parts, I provide a plurality of sectional members 21, 21. These rest on the upper surface of the bottom lead 3 and have wiping contact there- 80 with so as not to interfere with the movement of that lead during the operation of the grate. Said members 21 are suspended from the members 19 by having their hooked upper ends engage over angle plates 22 carried by the members 19, as shown. The 85 members 21 are slid endwise on the angle members 22 in the installation of the furnace and are held in substantially tight contact with each other by end brackets 23, 23 adjustably secured by bolts and elongated slots 90 to the sides of the stools 7, as shown in Figs. 2 and 3.

By having the members 21 hooked over the supporting bars 22, said members 21 may be raised upward by the droppage carried 95 under them by the bottom lead 3, and to prevent the members 21 being moved by the droppage off of said bars 22, I provide guard plates 24 extending over the hooked ends of the members 20, as shown in Figs. 1 and 3. 100 These plates 24 are suitably secured to the cross-beams 19. The members 20 and 21 bearing against the top and bottom leads of the grate 1 provide air seals between the various compartments 17 formed by said 105 members and the beams 19 and prevent one compartment leaking into the other when placed under draft from the main supply conduit 14.

Arranged beneath the lower lead 3 are 110 skids or rails 25. These extend substantially the full length of the grate and support said bottom lead 3. Between said skids 25 extend metal plates 26, 26. These form a roof or top wall for the conduit 14 and 115 divide the same from the lower lead 3. Said plates 26 where they engage the skids 25 have their side edges bent to rest on and conform to the base flanges of said skids, as shown, to provide an air seal between the 120 plates and skids. The outermost plates 26 at each side of the grate 1 have their side edges flanged upward, as at 27, and these flanges are secured to members 28 extending between the several stools 7, as clearly shown 125 in Figs. 2 and 3. These members 28 are made of cast metal and the lower lead 3 rests on them. Between the flanges 27 and the members 28 are wear bars 29 made of steel. This takes the friction of the lower 130

lead and saves the members 28 from wearing down beyond the bars 29.

Mounted on the members 28 are angle bars 30. These form ledge plates for the lower lead 3 and extend between the stools 7 and are adjustably secured by a bolt and slot connection to the members 28 so that they may be adjusted against the side edges of said lower lead 3 to provide an air seal between the lower lead and the members 28.

The skids 25 are supported from below by a plurality of transverse members 31, as clearly shown in Fig. 1. These are in substantially vertical alignment with the transverse members 19 and are supported at their ends by webs 32 on the stools 7, as shown in Fig. 3. The plates 26 extend between these members 31 and the skids 25. To close the spaces between the plates 26 and the under surface of the lower lead 3 in line with the members 19, I provide a plurality of members 33. These are secured in place in any suitable manner and bear against the under side of the bottom lead 3 in somewhat the same manner as do the members 21.

The grate 1 is made of connected links or parts with air passages between them, as customary in chain grate construction, and, as an aid in preventing the passage of air from one compartment 17 to another through the lower lead 3, the chambers formed between that lead and the plates 26 fill with ash from the droppage through the top lead 2.

The conduit 14 beneath the stoker is common to all of the vertical ducts 16 and also to all of the compartments 17 formed between the top and bottom leads of the grate. For controlling the admittance of draft into these several compartments 17, I provide a plurality of damper plates 34. These, as shown in Figs. 2 and 3, are hinged to members 35 extending between the several stools 7 below the parts 28 and are adapted to be swung from a position closing the spaces between the members 28 and the bottom walls 15 of the vertical air ducts 16. Each vertical duct 16 has one of these dampers 34, thereby permitting any one of the ducts 16 to be cut out or supplied with air to the extent desired.

For actuating the dampers 34, I employ three shafts 36, 37, and 38. These extend into the conduit 14 from a point outside the front of the furnace and through a vertical plate 39 extending across the front of the conduit 14 and closing it at the front of the furnace. These shafts are telescoped and the one 36 extends the full length of the conduit 14; that is, it extends from the front of the furnace back to the rear end of said conduit. The rear end of said shaft 36 is journaled in a bracket 40 at the rear end of the conduit 14, as shown in Fig. 1.

The next shaft 37 extends back to and in

line with the stools 7 forming the rear sides of the intermediate duct 16, as shown in Fig. 6. The rear end of this shaft is journaled in a bracket 41, as shown in Fig. 1. The next shaft 38 is also tubular and is not as long as the one 37. Said shaft 38 extends into the conduit 14 back to and in line with the stool 7 forming the rear sides of the forward vertical duct 16 and is journaled in a bracket 42. Each of these shafts is provided with two radial arms 43, 43, which are connected by rods 44, 44 with the associated damper plates 34, as shown in the drawings.

At the outer end of each of these shafts 36, 37, and 38 is a radial arm 45, and pivoted to these are connecting rods 46, 46, one for each of said arms. The rods 46 are pivotally connected to upright operating levers 47, 48, and 49, respectively, as shown in Fig. 1. These levers have suitable latch members operating in connection with notched sectors 50, 50, as shown in Fig. 6, for holding the levers in any of their several positions of adjustment.

The conduit 14 may be supplied with air from any suitable source and in any preferred manner, but in the drawings I have shown two blowers 51, 51 operated by electric motors 52, 52 for this purpose. These parts are arranged at the front end of the conduit 14 and forward of the front wall 39. The blowers open into the conduit 14 through this wall for supplying air thereto.

The furnace structure shown and described operates as follows. Fresh or green fuel is fed into the furnace through the hopper 5 at the front end of the grate and is carried through the combustion chamber in a layer on the top lead 2 of the grate. To supply draft to the fuel bed for aiding combustion, air is supplied to the conduit 14 and from that to the under side of the top lead 2 from any one or all of the vertical ducts 16 at the sides of the grate 1.

Should it be desired to supply a draft to the front section of the fuel bed, that is, the section adjacent the place of incoming fuel and covering the front compartment 17, the hand lever 47 is actuated to open the foremost damper plates 34. This allows air from the conduit 14 to flow into the first compartment 17 and places the incoming fuel layer under forced draft.

Should it be desired to supply air to the next or middle section of the fuel bed, that is, the fuel bed over the middle compartment 17, the hand lever 48 is operated to open the dampers 34 for that compartment and air is supplied thereto from both sides of the furnace through the mid-ducts 16.

On the other hand, should it be desired to supply the last of the fuel bed with a draft, the hand lever 49 is operated to open the rearmost dampers 34. Should it be desired

to cut out any of these compartments 17 and allow any of the others to be opened to draft, the damper plates for the particular compartments to be closed are closed and those to be opened are opened through the levers for that or those compartments, as is apparent.

Thus during the operation of the furnace, either the entire grate surface may be placed under forced draft, or any section or sections thereof, as may be desired. Manifestly, the fuel bed may be placed under that draft most suitable to gain proper and economical consumption of fuel and these draft conditions may be made suitable to the nature of the fuel being handled and also to the rate of fuel feed.

It is to be observed that the conduit 14 is common to all of the ducts 16, 16 at both sides of the grate 1, and further that the communication of each duct 16 with the conduit 14 is of the full width of the duct 16 and also that the latter is the full width of the compartment 17 which it supplies. This allows supplying air to the grate at an even and substantially continuous flow without high velocity and thus avoids blowing holes in the fuel bed by the draft being forced too rapidly through it. Furthermore, the entire grate surface covering such compartment 17 is placed under draft through its entire extent or area, thus gaining adequate and complete supply of air to the fuel bed sections over such areas. Moreover, by having the conduit 14 common to all of the vertical ducts 16, the pressure in the conduit 14 may be maintained constant and at that degree most suitable to secure an even and gentle flow of draft regardless of the number of ducts 16. Then again, having the conduit 14 beneath the stoker 1 and its communication with the upper chain lead 2 around the sides of the stoker, avoids leading the draft into the stoker through the side walls of the furnace from points exterior, thus reducing the width of the furnace to the minimum and enabling the same to be built in battery form as there are no parts of the draft structure projecting beyond the sides of a stoker to interfere with or prevent that. Again, by having a single supply conduit 14 and that common to all of the ducts 16, avoids the expense of building and use of separate supply conduits for the various vertical ducts 16, as heretofore. Other and further objects of my invention will be apparent to those skilled in the art to which my invention relates.

While I have shown and described herein in detail a structure embodying the features of my invention, it is of course to be understood that the details of construction and arrangement of parts may be variously changed and modified without departing from the spirit and scope of my invention.

I claim as my invention:

1. In a furnace, the combination of a grate, a plurality of air-ducts on opposite sides of said grate and opening beneath the fuel supporting portion of said grate for supplying draft thereto, the ducts at one side of said grate being opposite the corresponding ducts on the other side of said grate, a single conduit beneath said grate and between the ducts at the sides thereof, said conduit being common to all of said ducts for supplying air thereto, a damper for each duct, a plurality of shafts between said ducts, one for each set of opposite ducts, and means connecting each shaft with the dampers of its associated ducts so that the dampers of one set of ducts may be actuated independently of the dampers of any other set.

2. In a furnace, the combination of an endless chain grate having upper and lower leads, a plurality of beams extending transversely across the space between said leads for dividing said space into a plurality of compartments, members associated with said beams and extending on opposite sides thereof, said members being in contact with said upper and lower leads, respectively, for providing air seals between said compartments along said beams, a single conduit beneath the lower lead and common to all of said compartments, and means for supplying air to said compartments from said conduit around the sides of said lower lead.

3. In a furnace, the combination of an endless chain grate having upper and lower leads, skids extending longitudinally of said grate beneath the upper lead for supporting the same, beams extending transversely across the space between said leads for dividing said space into a plurality of compartments, said beams being against the under sides of said skids, members associated with said beams and bearing against said upper and lower leads, respectively, for providing air seals between said compartments along said leads, the uppermost of said members extending between said skids for closing the spaces between the same along said beams, and means for supplying air to said compartments for placing the upper lead under a draft.

4. In a furnace, the combination of an endless chain grate having upper and lower leads, skids extending longitudinally of said grate beneath said upper lead for supporting the same, beams extending transversely across the space between said leads for dividing said space into a plurality of compartments, said beams engaging the under sides of said skids, members associated with said beams and engaging against the upper and lower leads, respectively, for providing air seals between said compartments along said beams, the lowermost of said members being mounted on said beams in a manner

- permitting raising of said members by drop-
page carried under them by said lower lead,
and means for supplying air to said com-
partments around the sides of said lower
lead for placing the upper lead under draft.
5. In a furnace, the combination of an
endless chain grate having upper and lower
leads, skids extending longitudinally of said
grate beneath said upper lead for support-
ing the same, beams extending transversely
across the space between said leads for di-
viding said space into a plurality of com-
partments, said beams engaging the under
sides of said skids, members associated with
said beams and engaging against the upper
and lower leads, respectively, for providing
air seals between said compartments, means
providing a hooked connection between the
lowermost of said members and said beams
permitting said members to be raised by
droppage carried under them or said lower
lead, means limiting the raising of said
members by said droppage, and means for
supplying air to said compartments around
the sides of said lower lead for placing the
upper lead under draft.
6. In a furnace, the combination of an
endless chain grate having upper and lower
leads, stools at the sides of said grate, beams
extending transversely across the space be-
tween said leads for dividing said space
into a plurality of compartments, means
associated with the upper portions of said
beams and engaging the under side of
said upper lead for providing air seals be-
tween said compartments along the top of
said beams, an angle plate secured to
the lower portion of each beam, a plu-
rality of shoe members hooked over said
angle plates and bearing downward against
the upper surface of said lower lead, mem-
bers adjustably mounted on said stools at
the ends of said beams for keeping the in-
terposed shoe members in contact with each
other, and means for supplying air to said
compartments around the sides of said lower
lead for placing the upper lead under draft.
7. In a furnace, the combination of an
endless chain grate having upper and lower
leads, upright stools at one side of said
grate, members extending between said
stools along the side edges of said upper and
lower leads and supporting the same, ledge
plates adjustably mounted on said members
for the respective grate leads, means between
said leads for dividing the space therebe-
tween into a plurality of transverse com-
partments opening upward to said upper
lead, door frames between said stools, doors
carried by said frames for closing the open-
ings therein, a single conduit below said
lower lead and common to all of said com-
partments for supplying air thereto, means
dividing said conduit from said lower lead,
plates between said stools and extending
from said frames to upper ledge plate sup-
ports and the floor of said conduit, respec-
tively, for providing air ducts from said
conduit to said compartments, dampers
hinged to the lower ledge plate supports,
one for each duct, and means for actuating
said dampers.
8. In a furnace, the combination of a
grate having a traveling portion, stools at
the sides of said grate, members between
said stools and extending under side edges
of said traveling grate portion for support-
ing the same, said members being of cast
metal, and wear strips of harder metal se-
cured to said cast members and engaged by
said grate for preventing the cast members
wearing below said strips.
9. In a furnace, the combination of a
grate, a plurality of air ducts on opposite
sides of said grate and opening beneath the
fuel supporting portion thereof for supply-
ing draft thereto, a single conduit beneath
said grate and between said ducts, said con-
duit being common to all of said ducts for
supplying air thereto, the ducts on one side
of said grate being opposite the ducts on
the other side thereof, a hinged damper for
each duct, a plurality of shafts of various
lengths extending into said conduit between
said ducts, said shafts being telescoped on
each other and arranged one for each set of
opposite ducts, means connecting each shaft
with the dampers of its opposite ducts for
opening and closing the same, and means for
actuating said shafts and independently of
each other.

In testimony that I claim the foregoing as
my invention, I affix my signature this 10th
day of December, A. D. 1921.

HERMAN A. POPPENHUSEN.
